LLP

(57) **CLAIM**

The ornamental design for a building element for floors, walls, and roofs, as shown and described.

DESCRIPTION

1. Building element for floors, walls, and roofs

1.1 : Perspective

1.2 : Perspective

1.3 : Front

1.4 : Back

1.5 : Right

1.6 : Bottom

1.7 : Top

The dotted lines indicate elements for which no protection is sought and is not a part of the view.

The building element for floors, walls, and roofs is shown with a symbolic break in its length. The appearance of any portion of the article between the break lines forms no part of the claimed design.

1 Claim, 7 Drawing Sheets
